DIGITAL CALENDAR CLOCK OR SIMILAR ARTICLE

Riki Watanabe, Tokyo-to, Japan, assignor to Kabushiki
Kaisha Koparu, Tokyo-to, Japan

Filed Nov. 24, 1971, Ser. No. 202,047

Claims priority, application Japan June 2, 1971

Term of patent 14 years

Int. Cl. D10—01

U.S. Cl. D42—7 H

FIG. 1

FIG. 2

FIG. 3

FIG. 4

FIG. 1 is a front perspective view of a digital calendar clock showing my new design;

FIG. 2 is a front elevational view thereof;

FIG. 3 is a left side elevational view thereof, the right side being a mirror image thereto;

FIG. 4 is a bottom rear perspective view thereof.

I claim:

The ornamental design for a digital calendar clock or similar article, substantially as shown and described.
